UNITED STATES PATENT OFFICE.

EDWIN H. FORD, OF HARTFORD CITY, INDIANA.

TOP FOR METER-BOXES.

974,650.

Specification of Letters Patent. Patented Nov. 1, 1910.

Application filed June 22, 1909. Serial No. 503,594.

To all whom it may concern:

Be it known that I, EDWIN H. FORD, a citizen of the United States, residing at Hartford City, in the county of Blackford and State of Indiana, have invented certain new and useful Improvements in Tops for Meter-Boxes, of which the following is a specification.

This invention relates to covers for manholes, street valves, and more particularly to meter boxes, wherein meters are placed for measuring water and gas; and the object of the invention is to provide the above specified boxes with covers which are easily and conveniently placed and locked in operative position, and unlocked and removed from said boxes.

I accomplish the objects of the invention by means of the construction illustrated in the accompanying drawings, in which—

Figure 1 is a central vertical sectional view through a meter box, showing my invention in operative position. Fig. 2 is a fragmentary detail sectional view, on an enlarged scale, through the locking device by which the cover is secured to the meter box top. Fig. 3 is a detail in horizontal section of the meter box, on an enlarged scale, showing the retaining lug in an underside plan view. Fig. 4 is a cross section of the construction shown in Fig. 3. Fig. 5 is a central vertical sectional view of the locking device, taken at a right angle plane line to that on which Fig. 2 is taken, except that the worm is shown in elevation.

In the drawings, 1 represents the casing that forms the body of the meter box, which body is generally composed, in modern meter box construction, of vitrified tile. The body 40 1 is let into the ground a distance so that the upper end of the box 1, in operating position, stands flush with the surface of the ground. The top of the meter box consists, primarily, of an annular collar 2, of a diameter somewhat larger than the meter box, so as to provide an intervening space 3 adapted to receive the tying cement 4 employed in securing said collar to the body 1. The collar 2 is provided with the integrally 45 formed annular extension 5. As shown in the drawings, the extension 5 is formed on an incline which terminates into the horizontally and annularly projecting ledge 6. This ledge projects inwardly and beyond the internal surface of the box 1, and provides the means by which the lid or cover is se-

cured to the collar 2. As the ledge 6 extends entirely around the box it at once becomes apparent that the cover can be secured to the collar 2 in any position in which 60 said cover is placed upon said collar. The edge of the ledge 6 is beveled on its upper and lower edge, to facilitate the action of the locking device employed to lock the cover fast to the collar 2. The cover 10 consists of a circular plate adapted to fit and seal the opening in the collar 2. The cover 10 is beveled on its lower edge, the plane of the incline corresponding to the inclined portion 5 of the collar 2, so that a neat joint 76 will be made when the collar and cover are in operative position.

To prevent surface water from gaining access to the meter box, I provide the gasket 12 which is embedded into the under surface of the cover 10. This gasket rests upon the annular rib 13 formed on the upper surface of the ledge 6. The collar 2 and cover 10 are formed so that when the latter is secured in position the cover will rest entirely 80 upon the gasket 12. The cover 10 is provided with a locking device by which it is made fast to the collar 2. This locking device consists of the worm 15, provided with external threads which engage the beveled 85 projecting edge of the annular ledge 6, of the collar 2. A bolt 16, having a suitable head 17 to receive a specially formed wrench, passes through the cover 10, and the lower end of the bolt 16 is made square to engage 90 a corresponding hole in the body of the worm 15, so as to impel rotation of the latter. The worm 15 is held in position on the bolt 16 by means of the transverse pin 18, and a split-washer 19 is inserted between 95 the face of the worm and the pin, to provide a buffer, so as to prevent the worm from working loose through vibration. By means of the annular ledge 6 and the worm 15, it will be seen that it is not necessary 100 to place the cover 10 into any particular position upon the collar 2, as the construction admits of the worm 15 taking hold of the ledge 6 at any position in which the cover 10 is placed on said collar. The use of the 105 worm as shown in the drawings, not only permits the cover to be drawn tightly against the collar 2, but the unscrewing of the worm loosens and forces the cover upwardly away from the collar, so that the 110 cover may be easily and conveniently removed by the hands without the use of tools.

This movement of the cover 10 is a result of the pitch of the threads on the periphery of the worm 15 working against the stationary ledge 6. This feature is of special importance in this class of work, since many refractory covers are met with, occasioned, generally, by rust, dirt, etc. Turning the worm in a direction to draw the cover tightly against the collar naturally centralizes the pressure around that portion of the cover adjacent to said worm. This pressure may cause the opposite side of the collar to raise up thereby preventing a uniform tight joint around said cover. Therefore, to equalize the pressure on the side of the cover opposite the worm, and to secure an equal distribution of the strain around the entire circumference of the cover, so as to seal the opening leading into the meter box, I provide the cover 10 on its underside opposite the worm 15, with the integral hook 25 which extends under the projecting ledge 6. See Fig. 4. The face of the hook, as shown, is cut on an incline so that when the cover is forced slightly in the direction in which the hook projects, caused by the action of the worm 15, the side of the cover containing said hook will be forced down tightly upon the rib 13, thereby making a tight joint entirely around the cover.

While the drawings show and the specification describes the invention in connection with water and gas meter boxes, it will be seen that the invention can be employed, without change, on manholes, street valves, etc., without departing from the spirit of the invention.

Having thus fully described my said invention, what I desire to secure by Letters 40 Patent, is—

1. A body portion having means to engage a cover locking device, a cover, and a cover locking device including a worm to engage said means on the body and adapted 45 to lower and raise said cover to and from said body without rotating said cover.

2. A body portion having means to engage a cover locking device, an annular rib on said body, a cover, a gasket carried 50 by said cover adapted to engage said rib on the body, and a cover locking device including a worm to engage said means on the body and adapted to lower and raise said cover to and from said body without rotating said cover.

3. A body portion provided with an internal opening bounded by an inwardly projecting ledge, a cover adapted to close said opening, and a locking device including a worm provided with external threads adapted to engage the projecting ledge for unlocking and forcing said cover to move upwardly from said body portion. 60

4. A body portion provided with an opening bounded by an inclined extension terminating in an annularly projecting ledge, a cover to close said opening in said body, and a revoluble locking device engaging said ledge when moved in one direction to tightly lock the cover upon the body portion and to 70 release and raise said cover up from said body portion when moved in the reverse direction.

5. A body portion provided with an opening bounded by an inclined extension 75 terminating in an annularly projecting ledge, a cover to close said opening in said body, a revoluble locking device engaging said ledge when moved in one direction to tightly lock the cover upon the body portion and to release and raise said cover up from said body portion when moved in the reverse direction, and a hook on said cover opposite the locking device and adapted to contact the lower edge of said ledge, as and for the purposes 80 set forth. 85

6. A body portion provided with an opening bounded by an inclined extension terminating in an annularly extending ledge, an annular rib on said ledge, a cover to close 90 the opening in said body, a gasket carried by said cover and adapted to rest upon said annular rib, a revoluble locking device adapted to engage the ledge when moved in one direction to tightly lock the cover upon 95 the body portion and to release and raise said cover up from said body portion when moved in the reverse direction, and a hook formed on the under side of the cover and opposite the locking device and adapted to 100 contact the ledge on said body, as and for the purposes set forth.

In witness whereof I have hereunto set my hand and seal at Indianapolis, Indiana, this 29th day of May, A. D. one thousand 105 nine hundred and nine.

EDWIN H. FORD. [L. S.]
